COLLAR HOLDER

Amedeo Morvillo, Providence, R. I., assignor to Spear & Susskind, a copartnership composed of Alfred Spear and Louis Susskind, both of Providence, R. I.

Application March 11, 1935, Serial No. 10,472

2 Claims. (Cl. 24—83)

My present invention relates to collar holders, and has particular reference to an improved construction therefor.

The collar holders now in use include a pair of jaws which are rigidly or flexibly locked together, each jaw being adapted to slip over a collar edge for releasable attachment thereto. This construction has disadvantageous features, as the collar holder must be put on after the tie is tied, and its resilient grip cannot be too strong, to prevent tearing or pull on the fabric. The collar holders therefore tend to slip during use, and are not suitable for stiff collars.

The principal objects of my invention are to provide a novel collar holder construction which can be used with any kind of collar, which cannot slip or become loose, and which may, and preferably is, attached to the collar before it is put on.

With the above and other objects and advantageous features in view, my invention consists of a novel arrangement of parts more fully disclosed in the detailed description following, in conjunction with the accompanying drawing, and more specifically defined in the claims appended thereto.

In the drawing,

Fig. 1 is a view, partly broken away, showing the novel collar holder in use;
30 Fig. 2 is a view showing the attachment of the collar holder parts to the collar points;

Fig. 3 is a view showing the collar holder parts releasably engaged;

Fig. 4 is a section on the line 4—4 of Fig. 3;
35 Fig. 5 is a plan view of a modified construction;
Fig. 6 is a side view of Fig. 5, and

Fig. 7 is a rear perspective view showing a modified type jaw construction.

I have found it desirable to provide a collar holder having releasably engageable gripping jaws, whereby the jaws may be independently secured to the collar points, and then engaged to complete the collar holder. This construction permits use of a strong clamp, as each jaw may be readily locked to its collar point, and the twisting and pulling necessary when a collar holder is inserted after the tie has been made, is eliminated. Moreover, the holder may be used on any type of collar, soft or starched, and does not mar the collar, as there need be no sliding movement of the jaw for securing to the collar point.

The improved collar holder 10 has the standard appearance of collar holders when in use, as indicated in Fig. 1; the holder comprises two

jaws 11, 12, see Fig. 2, which are detachably securable, and may therefore be mounted on the collar points before the collar or the shirt is put on. The jaw 11, see Fig. 3, has an eye 13, and the jaw 12 has a tongue 14 removably insertable therethrough, these elements functioning as releasably engageable catch and latch parts.

Referring now to Fig. 4, the jaws 10, 11 include front elements 15 and back bars 16 spaced therefrom and secured thereto, as by rolling fingers from the inner parts of the front elements over the inner ends of the back bars, or by welding, soldering, or the like. Each back bar has a clamp screw 17 threaded therein, having a 10 rounded contact head 18 and a finger wheel 19, whereby the clamp screw may be turned to grip a collar point between the back of the front element and the contact head. The tongue 14 is preferably slightly offset, see Fig. 4, to permit 20 aligning of the two jaws.

The mounting of the novel collar holder is now evident. The two jaws are separately secured to the collar points by clamping the points between the front elements and the contact heads, whereby the jaws are rigidly locked in place, with no formation of slide marks or marring of the collar finish. The collar is then buttoned and the tie tied; then the tongue of one jaw is inserted into the eye of the other jaw, and the assembly is 30 completed.

If desired, an intermediate link may be used, to increase flexibility. Thus, as illustrated in Figs. 5, 6, the jaw 20 has at least one intermediate link 21 linked at one end thereto, and the jaw 35 22 has a tongue 23 detachably engageable with the other end of the link. Any type of jaw or connection may be utilized; if preferred, a spring type jaw construction such as for example illustrated in Fig. 7, may include two jaws 24, 25 each 40 having front bars 27 and spring back bars 28 secured to the front bars at one end and having pressure parts 29 at the other end. The jaw 24 has an eye 30 and the jaw 25 has a cooperating tongue 31.

The improved construction is applicable to other uses requiring two detachable lock parts which are releasably engageable or joinable, for example, chains for personal wear, curtain chains, and the like.

Although I have described two forms of clamping arrangements, any other suitable form may be used; moreover, the front bars and back bars may be made of sheet metal, wire, or other suitable material, and the releasable engaging parts 55

may be of the hook and eye type as disclosed, or of any suitable catch or snap construction, without departing from the spirit and the scope of the invention as defined in the appended claims.

5 I claim:

1. A collar holder comprising a hook portion and an eye portion, said hook portion comprising an ornamental bar having a hook at one end, and means for releasably clamping one end of a 10 collar to the rear portion of the other end of said bar, said eye portion comprising an ornamental bar having an eye at one end engageable by said hook, and means for releasably clamping the other end of the collar to the rear portion 15 of the other end of said bar, each of said releasable clamping means including a bar clamped to the ornamental front of said collar holder having a portion thereof bent so as to be spaced in parallel relation with said ornamental front 20 portion, and a screw clamp riding in a threaded opening in the end of said bar, said clamp having a rounded head on the inner end thereof facing

the rear portion of said ornamental front portion of the collar holder.

2. A collar holder comprising a hook portion and an eye portion, said hook portion comprising an ornamental bar having a hook at one end, and means for releasably clamping one end of a 5 collar to the rear portion of the other end of said bar, said eye portion comprising an ornamental bar having an eye at one end engageable by said hook, an elongated link in said eye, and means for releasably clamping the other end of the collar to the rear portion of the other end of said bar, each of said releasable clamping means including a bar clamped to the ornamental front 10 of said collar holder having a portion thereof bent so as to be spaced in parallel relation with said ornamental front portion, and a screw clamp riding in a threaded opening in the end of said bar, said clamp having a rounded head on the inner end thereof facing the rear portion of said 15 ornamental front portion of the collar holder.

AMEDEO MORVILLO.
